CLAIM

The ornamental design for a cathedral fence section, as shown and described.

DESCRIPTION

FIG. 1 is a front perspective view of the cathedral fence section of the instant invention;

FIG. 2 is a front elevation view thereof;

FIG. 3 is a rear elevation view thereof;

FIG. 4 is a left elevation view thereof;

FIG. 5 is a right elevation view thereof;

FIG. 6 is a top plan view thereof;

FIG. 7 is a bottom plan view thereof; and,

FIG. 8 is a perspective view illustrating a plurality of assembled cathedral fence sections, the fence sections depicted with hidden lines form no part of the claimed design.
